DESIGN FOR A SHOE

Thomas J. Bushman, St. Louis, Mo.

Application December 22, 1934, Serial No. 54,554

Term of patent 3½ years

To all whom it may concern.

Be it known that I, Thomas J. Bushman, a citizen of the United States, residing at St. Louis, Missouri, have invented a new, original, and ornamental Design for Shoes, of which the following is a specification, reference being had to the accompanying drawing, forming part thereof.

Figures 2 and 3 are perspective views of the opposite sides of the same, showing my new design, the shoe being tilted slightly towards the point of view to illustrate more clearly its appearance.

I claim:
The ornamental design for a shoe substantially as shown and described.

THOMAS J. BUSHMAN.
